United States Patent Office

Des. 198,055
Patented Apr. 21, 1964

198,055

BOTTLE

Robert Sidney Dickens and Kenji Yoshizumi, Chicago, Ill., assignors to The Coca-Cola Company, Atlanta, Ga., a corporation of Delaware

Filed Aug. 5, 1963, Ser. No. 76,104

Term of patent 14 years

(Cl. D58—8)

FIG. 1

We claim:

The ornamental design of a bottle, as shown and described.
